UNITED STATES PATENT OFFICE

2,311,693

INTERNAL COMBUSTION ENGINE

Edward T. Rodgers, New York, N. Y., assignor to
 Rodgers Diesels Corp., New York, N. Y., a corporation of Delaware

Application December 12, 1939, Serial No. 308,859

2 Claims. (CL 123—81)

This invention relates to internal combustion engines and more specifically to engines of the Diesel type.

In general, it is an object of the invention to provide a device of the character described which will efficiently perform the purposes for which it is intended, which is simple and economical of construction, which can be expeditiously, conveniently and safely manipulated, and which can be readily manufactured and assembled.

Another object of the invention is to provide means for reciprocating and oscillating a plurality of sleeve valves in a single motor simultaneously and substantially without the use of gears; to provide such mechanism which uses linkage connections; and to provide a single mechanism for motivating not only the slide valves but also the high pressure fuel pumps for the various cylinders.

Another object of the invention is to provide, as a combined unit, a Diesel precombustion chamber and a resilient safety valve therefor; and to provide such a unit integral with a fuel nozzle.

Other objects of the invention will in part be 25 obvious and will in part appear hereinafter.

The invention accordingly comprises the features of construction, combination of elements and arrangement of parts which will be exemplified in the construction hereinafter set forth and the scope of the application of which will be indicated in the claims.

For a fuller understanding of the nature and objects of the invention, reference should be had to the following detailed description, taken in connection with the accompanying drawings, in which:

Figure 1 is a view in elevation, with parts cut away and partially in section, of a machine embodying one form of the invention;

Fig. 2 is a cross-sectional view of the device shown in Fig. 1 and taken along the line 2—2 of Fig. 1;

Fig. 3 is a view in perspective of portions of the device shown in Fig. 1;

Fig. 4 is a plan view of portions of the device shown in Fig. 1; and

Fig. 5 is a view in elevation of the upper part of one of the cylinders.

In the drawings, 10 denotes the outer casing of a Diesel engine having an intake manifold 12 which leads to the various ports 14 of the cylinders 16. The latter are alike. There is a sleeve valve 18 slidable within the cylinder wall and having one or more air intake and one or more

exhaust ports 19 registerable with ports 14. There is the usual piston 20 and piston rod 22 leading to main crank shaft 24.

5 A cylinder head 26 fits against the inner surface of the upper part of the sleeve valve and is held in place by the cylinder cap 28. There is a removable precombustion chamber 30 which is generally spherical and seats in a roughly cup-shaped portion of the cylinder head. A safety 10 compression release valve 32 seats in an exit passageway from the precombustion chamber. The valve is held in closed position by a spring 34 one end of which presses the valve into closed position and other end of which presses against a cap nut 36 screwed onto the cylinder head. A lever 38 is attached to an annular lifting cam 39. A rotation of the lever causes the release valve to be raised against the action of the spring whereby any compressed gas in the precombustion chamber may escape between the release valve and the cylinder head 26 to escape through vents 42 to the atmosphere. There may be a connecting rod 44 attached to the various levers 38 for operating them simultaneously.

Means are provided for oscillating and reciprocating the sleeve valves. These means extend along the cylinders at one side of the engine. They do not include gearing other than incidentally as a means for the transfer of energy. 20 This linkage system is shown in Figs. 2 and 3. The linkage system shown comprises a pair of connecting rods 52 extending laterally from cylinder to cylinder. Power from the main crank shaft is supplied to these rods by any convenient 25 means such as a link belt 54 which delivers power to sprocket gear 56 on shaft 58. A forty-five degree beveled gear 60 attached to the latter meshes with a similar gear 62 on a shaft 68. The latter is conveniently directed perpendicularly 30 toward the axis of one end cylinder 16. A crank pin 64 on gear 62 is attached to and causes the motion of one connecting rod 52.

The motion of the connecting rod 52 is transmitted to the sleeve valves 18 by respective suitable mechanisms. Those shown comprise, for each cylinder, a crank rod 66 pivoted at one end to the connecting rod 52 and, at the other end, to crank shaft 68 fixed in housing 70. Attached to the shaft 68 is a cam 72 which also acts as a crank in that a sliding ball joint 74 is fixed to a boss 74a in the face of the cam and connects with an extension 75. If desired, gear 62 may support boss 74a.

In order that there may be no trouble at dead center, there may be a second or supplementary

connecting rod 52 substantially parallel to the first rod 52. A second crank pin from one end of the supplementary rod 52 is fixed to a crank cheek 18 and the latter is rotatable about crank pin 64. Thus, when gear 62 moves, both connecting rods 52 move, the first connecting rod 52 being placed ninety degrees in advance of the second.

A plunger 80 in a high pressure fuel pump 92 is connected at its outer end through suitable elements to cam 72 from which the plunger receives its motion. The various cams 72 are oriented to operate the various plungers 80 at the proper times for the supply of fuel to the various cylinders 16.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all the generic and

specific features of the invention herein described and all statements of the scope of the invention which, as a matter of language, might be said to fall therebetween.

Having described my invention, what I claim as new and desire to secure by Letters Patent is:

1. In a Diesel engine, a plurality of cylinders, a plurality of respective sleeve valves, a plurality of respective fuel injector pump pistons, and respective means for oscillating and reciprocating each of said valves, said oscillation and said reciprocation being simultaneous, said means being also in the form of a cam for reciprocating said fuel pistons.

15 2. In a Diesel engine, a plurality of cylinders, a plurality of respective sleeve valves, a plurality of respective fuel injector pump pistons, and respective means for operating said pistons and for oscillating and reciprocating each of said valves, 20 said oscillating and said reciprocating being simultaneous, said means including cams for respectively operating said pistons, said cams also acting as for respectively oscillating and reciprocating said valves.

EDWARD T. RODGERS.

CERTIFICATE OF CORRECTION.

Patent No. 2,311,693.

February 23, 1943.

EDWARD T. RODGERS.

It is hereby certified that the name of the assignee in the above numbered patent was erroneously described and specified as "Rodgers Diesels Corp." whereas said name should have been described and specified as --Rodgers Diesels Inc.--; as shown by the record of assignments in this office; and that the said Letters Patent should be read with this correction therein that the same may conform to the record of the case in the Patent Office.

Signed and sealed this 2nd day of November, A. D. 1943.

Henry Van Arsdale,
(Seal) Acting Commissioner of Patents.
